UNITED STATES PATENT OFFICE

163,698

SOUND RECORDING AND REPRODUCING
MACHINE

Ernst Keller, New York, N. Y., assignor to Machine Tool Works Oerlikon, Administration Company, Zurich/Oerlikon, Switzerland, a company of Switzerland

Application May 20, 1950, Serial No. 10,068

Term of patent 14 years

(Cl. D26—14)

To all whom it may concern:

Be it known that I, Ernst Keller, a citizen of Switzerland, residing at 59 Park Avenue, city of New York, county of New York, State of New York, have invented a new, original, and ornamental Design for a Sound Recording and Reproducing Machine, of which the following is a specification, reference being had to the accompanying drawing, forming a part hereof.

Fig. 1 is a top plan view of a sound recording and reproducing machine, showing my new design;

Fig. 2 is a rear elevational view;

Fig. 3 is a front elevational view; and

Fig. 4 is a side elevational view.

I claim:

The ornamental design for a sound recording and reproducing machine, as shown.

ERNST KELLER.
